UNITED STATES PATENT OFFICE

2,458,417

DRY SHAVER

Frank Pollifrone, Mill Valley, Calif.

Application September 18, 1946, Serial No. 697,643

13 Claims. (Cl. 30—43)

1.

This invention relates to a dry shaver and has for an object to provide an improved dry shaver which is manually operated for rotating a spiral cutting member alternately in opposite directions to clip hairs cleanly from the face or elsewhere without danger of abrading the skin.

A further object of this invention is to provide a manually operated dry shaver that enables one to eliminate the necessity for a source of electricity in using a mechanical razor.

A further object of this invention is to provide a manually and mechanically operable dry shaver which uses a manually operated power stroke for rotating a cutter spiral in one direction in a hair cutting operation and simultaneously stores up energy in a spring for rotating the spiral in the opposite direction, which reverse rotation may be used either as a hair cutting operation, or may be used as merely a return movement of the spiral in preparation for the next manually powered rotation of the spiral.

A further object of this invention is to provide a dry shaver which, utilizing the same principles of operation, may be made with a single cutter spiral in the head, and likewise may be made with a plurality of hair-cutting spirals in the head, two, three, four or more, as may be desired.

A further object of this invention is to provide a dry shaver having a cleaning brush in combination therewith for cleaning the cutting spiral, which brush may be moved into and out of the brushing position, and wherein the brushing position is located on the side opposite the hair cutting side of the shaver head.

A further object of this invention is a dry shaver utilizing a cutter spiral which does not need any gear train to transmit the power from a hand operated lever, but instead, utilizes a manually advanced and spring power retracted driver ball point operating directly in the slot of the cutter spiral, cooperating with the sides of the slot but out of contact with the cutting edges thereof.

A further object of this invention is to provide a dry shaver which in one form has a cutter spiral with a double groove, one groove having sharp cutting edges, and the other groove with dull edges, cooperating with a driver pin or ball point.

With these and other objects in view, as will more fully hereinafter appear, the invention consists in certain novel features of construction and arrangement of parts hereinafter fully described and illustrated in the accompanying drawings; it being understood that various changes in the

2.

form and minor details of the construction may be made without departing from the spirit and scope of the invention.

Fig. 1 is a side view showing the closed side of the housing of the dry shaver of this invention;

Fig. 2 is a front view of the complete dry shaver;

Fig. 3 is a side view from the opposite side of Fig. 1;

10 Fig. 4 is a sectional view on line 4—4 of Fig. 3;

Fig. 5 is a top view of the cutter spiral head, partly broken away;

Fig. 6 is a sectional view on line 6—6 of Fig. 2;

15 Fig. 7 is an edge view of the manually operable spring type driver;

Fig. 8 is a side view of Fig. 7;

Fig. 9 is a side view of a four cutter spiral form of this invention;

Fig. 10 is a front view of Fig. 9, partly broken away;

20 Fig. 11 is a side view of a three cutter spiral form of this invention;

Fig. 12 is a side view of a two cutter spiral form of this invention, the housing being partly broken away;

Fig. 13 is a front view, partly sectional and partly broken away, of Fig. 12;

25 Fig. 14 is an enlarged detail showing the cooperation of the driver and driving groove of the multiple groove cutter spiral form;

Fig. 15 is an end view of Fig. 14;

Fig. 16 is an enlarged detail showing a friction reducing rotatable shell on the driver ball point;

Fig. 17 is a detail showing the cooperation of the driver guide, the driver ball point, and the spiral cutter, as well as the cutter spiral cleaner brush carried on the driver; and

Fig. 18 is an end view on line 18—18 of Fig. 17.

There is shown at 20 the complete dry shaver 40 of this invention in a form having a single cutter, but the principles and most of the details of the one-cutter form likewise apply to any of the multi-cutter forms shown in Figs. 9 to 13, inclusive; and identical reference numerals are applied where the details are identical. The dry shaver includes a housing 21, shaped somewhat as shown, having a front wall 22 and back wall 23, both cut away in a half-moon as at 24 along one edge and joined together by an edge wall 25 along the opposite edge, the bottoms being connected by a curved extension 26 of the edge wall 25; this curved extension ending where the half-moon cutaways 24 commence.

45 The upper end of the housing 21 is open and above the cutaways 24 the front and back walls

are joined by a short edge wall 27. Journalized in the short edge wall 27 and the upper end of the housing edge wall 25 is a cutter spiral 28. The cutter spiral 28 consists of a cylindrical member 30 having one or more cutter spiral grooves 31 extending along and in the cylindrical surface thereof. In the cutter grooves, the edges 32, where the grooves extend through the cylindrical surface, are sharpened so as to provide a cutting effect. If one groove is used as a driving groove 29 without also being a cutter groove, its edges are dull or smooth. Projecting from the ends of the cylindrical member 30, in alignment with the longitudinal axis thereof, are a pair of stub shafts 33. As shown in the various figures, the helix of the spiral groove may be varied as desired, and in the multi-cutter forms 20², 20³, and 20⁴ may be in opposite directions.

Holes 34 in the edge walls 25 and 27 provide bearings for journaling the stub shafts 33 of the cutter spiral 28. In order to rotate the spiral 28, a spring type driver 35 is provided in the form of a J-shaped spring arm whose short arm 36 is securely fastened as by rivets 37 to the inside of the lower end of the edge wall 25. Extending from the end of long arm 38 of the driver 35 is a neck 39 terminating in a ball point 40, of such diameter that it fits entirely within the cutter spiral groove 31. Inasmuch as the ball point 40 is below the surface of the cylindrical member 30, it does not contact the cutting edges 32 of the spiral groove 31, and the neck 39, being smaller than the diameter of the ball point 40 or of the groove 31, likewise cannot contact the groove cutter edges 32. As shown in Fig. 16, the ball point 40 may be enveloped in a shell 41 rotatable thereon and adapted to have a film of lubricating material therein, thus making a substantially frictionless driving point.

As shown in Fig. 5, the cutter spiral 28 has only one groove. In Figs. 17 and 18, two grooves are shown in the cutter spiral. In Figs. 14 and 15, four grooves are shown. When there are more than a single groove, the driver point 40 may extend into a cutter groove 31 with cutting edges 32, the same way in Figs. 17 and 18 as it does in Fig. 5, or instead, one of the multiple grooves may have dull or non-cutting edges, and such groove would be merely a driving groove 29. This is shown in Figs. 14 and 15, and, of course, may be equally applicable to any multi-groove form, including those shown in Figs. 10 and 13. In the multi-groove form with a driving groove 29, as in Figs. 14 and 15, the driving point 40, although shown as a ball point, need not necessarily be a ball point, due to the absence of any cutting edges, but may be a cylindrical pin completely filling the groove.

In order to maintain the spiral driving ball point 40 within the driving groove, guide pins 42 integrally extending from the opposite edges of driver arm 38 cooperate with guide slots 43 formed in the front and back walls of the housing 21 and parallel to the axis of rotation of the cutter spiral 28. When the dry shaver 20 is grasped in the hand and squeezed against the long arm 38 of the driver 25, the driver will be moved towards and to the position shown in dot-and-dash at 38' in Fig. 4, and the ball point 40 will cause the cutter spiral 28 to rotate. When the squeezing pressure is then released, the spring properties of the driver 35 will restore it to its original position, reversing the rotation of the cutter spiral 28 as it does so.

Fitted over the top end of the housing 21 is a

shaver jacket or slotted comb member 44, half-round in shape, and provided with a great plurality of parallel slots 45. When the shaver is held against and moved over the face, the beard hairs will project into these slots 45, and the rotation of the spiral cutter 28, under squeezing action, will cut them off cleanly and as close to the skin as the thickness of the jacket permits. Due to the pressure against the skin, the hair roots will bulge slightly, thus making the cutting action take place on a plane substantially identical with the surface of the skin. If desired, the shaver may be held against the skin during the reverse rotation of the cutter spiral under the spring action, or it may be slightly relieved therefrom.

In order to remove the hair clippings from the cutter 28, a brush 46 is provided on a base 47 in the form of a collar slidably and frictionally embracing the sides of driver arm 38, enabling the brush ends to be advanced into cleaning contact within the housing against the spiral cutter 28, and thereafter to be retracted therefrom when cleaning is completed. To clean the cutter spiral, it is actuated while the brush is in contact therewith.

While the guide slots 43 are shown as being formed in the housing front and back walls in the form disclosed in Figs. 1 to 6, inclusive, it is obvious that a separate frame member 48, as in Figs. 17 and 18, may be provided for these guide slots 43 and the bearing holes 34, and that they can be attached and assembled with the upper end of the housing in any suitable manner.

In Figs. 9 to 13, inclusive, several multi-cutter forms 20⁴, 20³ and 20², of this invention are shown, with the shaving heads 50, 51 and 52 placed at an angle to the plane of the housing so that they may be comfortably held against the skin on the face in the shaving operation. In these forms, the upper ends of the housings are formed into, or provided with, box-like units 53 in whose side walls 54 are located the bearing holes 34' for stub shafts 33 of the spiral cutters 28. The top and bottom walls 55 of the box-like units 53 are provided with the guide slots 43 to receive the guide pins 42' formed on an angle bar 56 extending from the driver 35', so as to maintain the driver ball points, one for each cutter spiral, within the spiral grooves for rotating the cutter spirals. As shown, the grooves of these several multi-cutter head cutter spirals may extend in opposite directions.

Shaver jackets or comb members 44' with slots 45' of a size and shape to fit over the plurality of cutter spirals are fitted over the box-like unit 53 and provide cooperating shearing members for each of the spiral cutters.

In operation, the dry shaver 20, 20⁴, 20³, or 20² is held in the hand at a comfortable angle on the face, and the driver is squeezed and released alternately causing the cutter spirals to be rotated with the jackets and clip the hairs extending through the jacket slots. The presence of the angular head in the multi-cutter forms determines the manner of holding the dry shaver in the hand, but in the single cutter form at 20, the shaver may be held so as to be squeezed by either the thumb or the fingers, as desired. From time to time, the brush 46 may be moved to cleaning position. In addition, the shaver jackets may be frictionally held in position, and be easily removable, permitting ready cleaning of the cutter spirals.

While certain desirable embodiments of the

invention have been illustrated and the mode of operation described, it is to be understood that the invention is not necessarily limited to the precise arrangements thus disclosed, but is to be regarded as broadly inclusive of any and all modifications falling within the scope of the appended claims.

What is claimed is:

1. A dry shaver comprising a housing, a spirally grooved cutter means journaled at one end of said housing, a slotted comb member on said housing end in cooperative juxtaposition with said spiral cutter means, means for alternately rotating said spiral cutter means in opposite directions, said rotating means comprising a spring driver member, one end of which is secured to said housing and the other end of which comprises a spiral groove engaging point, cooperative guide means on said driver member adjacent said point end and on said housing maintaining said point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

2. A dry shaver comprising a housing, a spirally grooved cutter means journaled at one end of said housing, a slotted comb member on said housing end in cooperative juxtaposition with said spiral cutter means, means for alternately rotating said spiral cutter means in opposite directions, said rotating means comprising a spring driver member one end of which is secured to said housing and the other end of which comprises a spiral groove engaging point, a friction reducing member on said point, cooperative guide means on said driver member adjacent said point end and on said housing maintaining said point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

3. A dry shaver comprising a housing, a spirally grooved cutter means journaled at one end of said housing, said spirally grooved cutter means comprising a plurality of individual cutter members, the grooves in adjacent cutter members extending in opposite directions, a slotted comb member on said housing end in cooperative juxtaposition with said spiral cutter means, means for alternately rotating said spiral cutter means in opposite directions, said rotating means comprising a spring driver member one end of which is secured to said housing and the other end of which comprises a spiral groove engaging point, cooperative guide means on said driver member adjacent said point end and on said housing maintaining said point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

4. A dry shaver comprising a housing, a spirally grooved cutter means journaled at one end

of said housing, a slotted comb member on said housing end in cooperative juxtaposition with said spiral cutter means, means for alternately rotating said spiral cutter means in opposite directions, said rotating means comprising a spring driver member one end of which is secured to said housing and the other end of which comprises a spiral groove engaging point, a collar slidably mounted on said driver member, a brush based on said collar adapted to be temporarily moved into cleaning contact with said spiral cutter means within said housing, cooperative guide means on said driver member adjacent said point end and on said housing maintaining said point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

5. A dry shaver comprising a housing, a spirally grooved cutter means journaled at one end of said housing, said spirally grooved cutter means comprising a single cutter member, a slotted comb member on said housing end in cooperative juxtaposition with said spiral cutter means, means for alternately rotating said spiral cutter means in opposite directions, said rotating means comprising a spring driver member one end of which is secured to said housing and the other end of which comprises a spiral groove engaging point, a collar slidably mounted on said driver member, a brush based on said collar adapted to be temporarily moved into cleaning contact with said spiral cutter means within said housing, cooperative guide means on said driver member adjacent said point end and on said housing maintaining said point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

6. A dry shaver comprising a housing, a spirally grooved cutter means journaled at one end of said housing, means for alternately rotating said spiral cutter means in opposite directions, said rotating means comprising a J-shaped spring driver member one end of which is secured to said housing and the other end of which comprises a ball point, said ball point engaging said spiral groove, cooperative guide means on said driver member adjacent said ball point end and on said housing maintaining said ball point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

7. A dry shaver comprising a housing, spirally grooved cutter means journaled at one end of said housing, a slotted comb member removably mounted on said housing end in cooperative juxtaposition with said spiral cutter means, means for alternately rotating said spiral cutter means in opposite directions, said rotating means comprising a J-shaped spring driver member one end

of which is secured to said housing and the other end of which comprises a ball point, a friction reducing member on said ball point comprising an enveloping shell rotatably mounted thereon, said ball point engaging said spiral groove, cooperative guide means on said driver member adjacent said ball point end and on said housing maintaining said ball point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

8. A dry shaver comprising a housing, a spirally grooved cutter means journaled at one end of said housing, said spirally grooved cutter means comprising a single cutter member, a slotted comb member removably mounted on said housing end in cooperative juxtaposition with said spiral cutter means, means for alternately rotating said spiral cutter means in opposite directions, said rotating means comprising a J-shaped spring driver member one end of which is secured to said housing and the other end of which comprises a ball point, said ball point engaging said cutter means within said spiral groove, cooperative guide means on said driver member adjacent said ball point end and on said housing maintaining said ball point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

9. A dry shaver comprising a housing, a spirally grooved cutter means journaled at one end of said housing, said spirally grooved cutter means comprising a plurality of individual cutter members, a slotted comb member removably mounted on said housing end in cooperative juxtaposition with said spiral cutter means, means for alternately rotating said spiral cutter means in opposite directions, said rotating means comprising a J-shaped spring driver member one end of which is secured to said housing and the other end of which comprises a ball point, said ball point engaging said cutter means within said spiral groove, cooperative guide means on said driver member adjacent said ball point end and on said housing maintaining said ball point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

10. A dry shaver comprising a housing, a spirally grooved cutter means journaled at one end of said housing, a slotted comb member removably mounted on said housing end in cooperative juxtaposition with said spiral cutter means, means for alternately rotating said spiral cutter means in opposite directions, said rotating means comprising a J-shaped spring driver member one end of which is secured to said housing and the other end of which comprises a

ball point, a collar slidably mounted on said driver member, a brush based on said collar adapted to be temporarily moved into cleaning contact with said spiral cutter means within said housing, said ball point engaging said cutter means within its spiral groove, cooperative guide means on said driver member adjacent said ball point end and on said housing maintaining said ball point in driving engagement within the groove in said spirally grooved cutter means, said housing being cutaway along at least a portion of one side providing operative access to said driver member whereby said housing may be manually held in shaving position to depress and release said spring driver member to alternately rotate said cutter spiral means.

11. A dry shaver comprising a housing, a spirally grooved cutter means journaled at one end of said housing, said spirally grooved cutter means comprising a plurality of individual cutter members, the grooves in adjacent cutter members extending in opposite directions, a slotted comb member removably mounted on said housing end in cooperative juxtaposition with said spiral cutter means, means for alternately rotating each of said spiral cutter means in opposite directions, said rotating means comprising a J-shaped spring driver member one end of which is secured to said housing and the other end of which comprises a ball point, said ball point engaging said cutter means within its spiral groove, cooperative guide means on said driver member adjacent said ball point end and on said housing maintaining said ball point in driving engagement within the groove in said spirally grooved cutter means, said housing being cutaway along at least a portion of one side providing operative access to said driver member whereby said housing may be manually held in shaving position to depress and release said spring driver member to alternately rotate said spiral cutter means.

12. In a dry shaver comprising a housing, a cylindrically spiralled cutter means journaled on its ends at one end of said housing, said cutter means having a plurality of spiral grooves, at least one of the grooves being a driving groove, the remaining grooves having sharpened cutter edges, and a spring driver member extending into said driving groove and movable therewith to impart rotation to said spiral cutter means.

13. In a dry shaver comprising a housing, a cylindrically spiralled cutter means journaled on its ends at one end of said housing, said cutter means having a plurality of spiral grooves, at least one of the grooves being a driving groove, the remaining grooves having sharpened cutter edges, and a spring driver member extending into said driving groove and movable therewith to impart rotation to said spiral cutter means, the edges of the driving groove also being sharpened.
